(57) **CLAIM**

The ornamental design for a pair of arms for inversion apparatus as shown and described herein.

DESCRIPTION

FIG. 1 is a front perspective view of a left arm portion of a pair of arms for inversion apparatus showing our new design;

FIG. 2 is a front view of the left arm portion of the pair of arms for inversion apparatus shown in FIG. 1;

FIG. 3 is a rear view of the left arm portion of the pair of arms for inversion apparatus shown in FIG. 1;

FIG. 4 is a top view of the left arm portion of the pair of arms for inversion apparatus shown in FIG. 1;

FIG. 5 is a bottom view of the left arm portion of the pair of arms for inversion apparatus shown in FIG. 1;

FIG. 6 is a first side view of the left arm portion of the pair of arms for inversion apparatus shown in FIG. 1;

FIG. 7 is a second side view of the left arm portion of the pair of arms for inversion apparatus shown in FIG. 1;

FIG. 8 is a front perspective view of a right arm portion of the pair of arms for inversion apparatus showing our new design;

FIG. 9 is a front view of the right arm portion of the pair of arms for inversion apparatus shown in FIG. 8;

FIG. 10 is a rear view of the right arm portion of the pair of arms for inversion apparatus shown in FIG. 8;

FIG. 11 is a top view of the right arm portion of the pair of arms for inversion apparatus shown in FIG. 8;

FIG. 12 is a bottom view of the right arm portion of the pair of arms for inversion apparatus shown in FIG. 8;

FIG. 13 is a first side view of the right arm portion of the pair of arms for inversion apparatus shown in FIG. 8;

FIG. 14 is a second side view of the right arm portion of the pair of arms for inversion apparatus shown in FIG. 8; and,

FIG. 15 is a front perspective view of the pair of arms for inversion apparatus shown in a position of use on an inversion apparatus drawn in the broken lines.

(Continued)

Those portions of the left arm for inversion apparatus and the right arm for inversion apparatus shown in broken lines are included for illustrative purposes only and form no part of the claimed design.

The broken lines in FIG. 15 illustrating an inversion apparatus depict environment and form no part of the claimed design. All other broken lines depict portion of the pair of arms for inversion apparatus that form no part of the claim design.

1 Claim, 15 Drawing Sheets
